CLAIM

The ornamental design for a toy building brick, as shown and described.

DESCRIPTION

FIG. 1 is a front, right side, and top perspective view of a toy building brick showing the new design; FIG. 2 is a front elevation view thereof; FIG. 3 is a rear elevation view thereof; and, FIG. 4 is a right side elevation view thereof, wherein the left side appears as a mirror image. The broken lines are for the purpose of illustrating portions of the article that form no part of the claimed design.
